UNITED STATES PATENT OFFICE.

AUGUST M. AUGENSEN, OF MAYWOOD, ILLINOIS, ASSIGNOR TO AMERICAN CAN COMPANY, OF NEW YORK, N. Y., A CORPORATION OF NEW JERSEY.

CAN-FEEDING MECHANISM.

1,326,903.

Specification of Letters Patent.

Patented Jan. 6, 1920.

Application filed April 15, 1915. Serial No. 21,545.

To all whom it may concern:

Be it known that I, AUGUST M AUGENSEN, a citizen of the United States, residing in Maywood, in the county of Cook and State 5 of Illinois, have invented a new and useful Improvement in Can - Feeding Mechanism, of which the following is a specification.

My invention relates in general to can-feeding mechanisms and has more particu- 10 lar reference to mechanisms of this character designed to transfer the filled and unheaded cans from the filling machines to the can-heading and closing machines, however as the invention is better understood it will 15 be manifest that it has other and more general application. In mechanism of the character described it is particularly desirable that the can be moved from one machine to the other smoothly and without jars or 20 shocks which will cause spilling of the contents.

A principal object of this invention is the provision of mechanism of the character described which will smoothly transfer the 25 cans from a filling or other machine to a can-heading or closing machine or the like and this without appreciably jarring the contents.

A further object of the invention is the 30 provision of such a mechanism which will receive cans from a single machine and deliver them to a number of other machines arranged appropriately.

A further object of the invention is the 35 provision of a machine of the character described which will be of economical construction and simple, durable and efficient operation.

Other objects and advantages of the in- 40 vention will be apparent as it is better understood from the following description when considered in connection with the accompanying drawing illustrating a preferred embodiment thereof.

On the drawings,

Figure 1 is a top plan view of a can-feeding mechanism embodying my invention;

Fig. 2 is a partial side elevation thereof looking from right to left in Fig. 1;

Fig. 3 is a section taken on the line 3—3 of Fig. 1; and

Fig. 4 is an enlarged view partially in horizontal section and partially in plan and showing certain details of construction.

For the purpose of illustrating my invention I have shown on the drawing a rotat- 55 ing disk 5, upon which the cans 6 are re- ceived from the filling or other machine or mechanism which, as it forms no part of my invention, is not shown on the drawing. The 60 cans are delivered to the disk in the direction of the arrow A in Fig. 1. The disk 5 em- braces a shaft 7 and is positioned between a spider 8 and a collar 9, carrying a bevel gear 10 (Fig. 3), both of which parts 8 and 9 are 65 keyed upon the shaft as at 11 to turn there- with. The disk may be merely held between the spider 8 and the collar 9 or it may be secured to either or both.

The cans are delivered from the disk onto a 70 conveyer 12 which, in the present instance, is divided into a plurality of lanes 13, 14 and 15. These lanes are defined by side guides 15' and two center guides 16 extending above and longitudinally of the conveyer 12 which 75 is of the belt or continuously traveling type. The spider 8 is provided with radially ex- 80 tends arms equaling in number the num- ber of lanes in the conveyer 12, as indicated at 17, 18 and 19, these arms being constructed 85 and arranged to accurately position the cans upon the disk and deliver them successively to the lanes 13, 14 and 15. The conveyer and disk move at a predetermined relative speed and one receives traveling power from the 85 other. This is through the medium of a sprocket chain 21 (Fig. 3) engaging a sprocket wheel 22' upon a shaft 23 carrying the sprocket wheels 22 for the conveyer and about a sprocket wheel 24 on a shaft 24' 90 carrying a bevel pinion 25 engaging the bevel pinion 10 of the collar 9. If desired, the chain 21 may be mounted in a housing 26.

Each of the arms 17, 18 and 19 is pro- 95 vided with an arcuately curved recess 27 upon its forward face, and into these re- cesses the cans are fed onto the disk. The recesses accurately position them and cause them to move about the conveyer against the guide 28 mounted in stationary position 100 along the forward side of travel of the disk, this guide preferably forming a continua- tion of the guide 15' at the adjacent side. One of the arms is adapted to deliver cans for the lane 15, which is the lane at the side 105 of the conveyer most remote from the re- ceiving point of the disk in its direction of travel. Cans carried by the arm 17 are re-

moved by the continuation 29 of the guide 15' at this side of the conveyer, which extends above the disk and over it into position to cause the cans to slide off into the 5 lane 15. The other two arms 18 and 19 carry slides or ejecting devices 31 which are adapted to push the cans from the holders into the lanes 13 and 14, those from the holder 18 going into the lane 13 and those 10 from the holder 19 into the lane 14. Each of these slides is operated by a lever 32 pivoted upon the arm between its ends at 33 and having one end connected with the slide by pin and slot engagement 34 and the other 15 end provided with a roller 35. The two levers 32 are arranged so that they, or their rollers, are at different distances from the shaft 7. Two cams 36 and 37 are appropriately positioned upon the under side of a 20 stationary cam bearing member 38, each of these cams being arranged to engage an appropriate roller 35 to produce a forward movement of its slide 31. The cam 36 is positioned in advance of the cam 37 and is 25 adapted to engage the roller 35 to operate the slide of the lever 18 and eject the can 6 carried by this lever into the lane 13, while the cam 37 is adapted to produce a similar ejection from the arm 19 into the lane 30 14. The cams 36 and 37, in the present instance, consist merely of sheet metal strips secured on the under side of the plate or cam bearing member 38 which as has been said is stationary. This member is mounted 35 upon a bracket 39 which is secured by bolts 40 to some fixed support 41 of the main frame and extends over the disk and forms a bearing at 42 for the upper end of the shaft 7. A spring or other suitable means 40 43 (Fig. 4) is provided for returning the slides to normal can-receiving position after each ejection.

After the cans are received by the conveyer they are delivered in any suitable 45 fashion from the lanes to the different machines for closing or heading them or for performing other functions as may be desired.

It is thought that the invention and many 50 of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

60 I claim:

1. A can-feeding mechanism comprising a rotating disk, means for accurately positioning the cans on said disk, a conveyer for receiving cans from said disk, and means 65 rotating with the disk and outwardly mov-

able at different points of delivery for successively positioning the cans on different parts of said conveyer.

2. A can-feeding mechanism comprising a rotating disk upon which the cans are received, means for accurately positioning the cans on said disk, a conveyer for receiving the cans from said disk, means rotating with the disk and cans for successively feeding cans from said disk into successive 70 lines, and actuating means for moving the feeding means outward at different points of delivery.

3. A can-feeding mechanism comprising a rotating table on which the cans are delivered, a fixed peripheral can-guiding device around a portion of the same, and means for ejecting said cans from said table comprising at different parts of the periphery a spider and ejectors mounted and movable 85 on said spider, and separate means for actuating each ejector.

4. A can-feeding mechanism comprising a rotating disk for receiving cans, means for accurately positioning the cans on said disk, a conveyer having lanes for receiving the cans from said disk, cams and movable means carried with the disk and operated by the cams for ejecting the cans from said disk to said conveyer into predetermined different 90 lines on the same.

5. A can-feeding mechanism comprising a rotating disk, can holding arms rotatable with said disk, ejecting devices for discharging cans from said disk each ejecting 100 device having its individual operating means, a fixed ejecting device for removing the most advanced can, and means for operating the ejecting device of a succeeding can at a less advanced point.

6. A can-feeding mechanism comprising a rotating disk upon which the cans are received, can-holding devices above the disk and rotatable therewith, ejecting devices carried by said holding devices, means operable respectively when the ejecting devices are in different predetermined positions for operating them to eject the cans held thereby, and stationary means for operating said ejecting devices respectively at different 110 predetermined points in their travel.

7. A can-feeding mechanism comprising a rotating disk upon which the cans are received, a conveyer, ejecting devices for moving said cans from the disk to said conveyer at different points, and cams which are differently arranged and separately actuate said ejecting devices.

8. A can-feeding mechanism comprising a rotating table upon which the cans are received and supported, a can holding device which is fixed relative to and is rotatable with said table, means for ejecting cans from said device at a predetermined point, a second outwardly movable can holding de-

vice rotatable with the table, and means for ejecting cans from said second can holding device at a different predetermined point.

9. A can-feeding mechanism comprising a 5 rotating table upon which the cans are received and supported, a can holding device which is rotatable with said table, means for ejecting cans from said device at a predetermined point, a second can holding device 10 rotatable with the table, means for ejecting cans from said second can holding device at a different predetermined point, and a conveyer which receives the two series of cans on different parts of its surface.
- 15 10. A can-feeding mechanism comprising a rotating table upon which the cans are re-

ceived and supported, a can holding device which is rotatable with said table, fixed means for removing cans from said device at a predetermined point, a second can holding 20 device rotatable with the table, and means movable toward the cans and away from the center of rotation for ejecting the cans from said second can holding device at a different predetermined point.

Signed in the presence of two subscribing witnesses.
